ELECTRICAL SWITCH

Willard Rhea, Piedmont, Mo.

Application January 17, 1938, Serial No. 185,431

3 Claims. (Cl. 200—6)

My invention relates to electrical switches and more particularly to snap switches wherein a plurality of contacts are employed.

One of the principal objects of my invention is to provide an improved form of snap switch wherein groups of contact members are connected together by a single action of the switch operating medium.

Another object of my invention is to provide a device of the above described character which is simple in construction, efficient in operation, easy of assembly, durable in use and economical in manufacture.

Other objects and advantages will be apparent from the following description, appended claims and annexed drawings.

Referring to the drawings wherein like reference characters designate like parts throughout the several views:

Fig. 1 is a top plan view of my invention.

Fig. 2 is an end elevation thereof.

Fig. 3 is a sectional view taken on the line 3—3 of Figure 1.

Fig. 4 is a top plan view of the mounting or switch box, certain of the parts being removed therefrom.

Fig. 5 is a perspective view of the frame illustrating the arrangement of the blades.

Fig. 6 is a detail enlarged sectional view taken on the line 6—6 of Figure 4.

In practicing my invention I employ a mounting 8 preferably in the form of a switch box having the usual side and end walls 6 and 7 respectively and of an elongated configuration having an open top.

The upper faces of the side walls are recessed and accommodate therein offset sections 8 of depending contact members 9, the contact members on one side forming one group and the contact members on the opposite side forming another group. The lower ends of the contact members of one group are folded to form channels opening in one direction and the ends of the contact members of the oppositely disposed group are folded to form channels opening in an opposite direction for a purpose hereinafter made apparent.

The upper sections of the end wall 7 of the switch box are formed with downwardly extending V-shaped slots 10 and accommodate therein pivots 11 fashioned on an elongated frame 12.

Said frame comprises longitudinally extending side bars forming contact blades 13 connected together at the ends thereof by means of integrally formed transverse bars 14. The contact blades

are angularly disposed relative to the longitudinal plane of the bars 14 for seating within the channels of the contact members 9. The transverse bars 14 are fashioned with a depending yoke having a longitudinally extending member 15. Said member intermediate of the length thereof is fashioned with an enlarged section 16 having a projection 17 for accommodating and forming a seat for one end of a coil spring 18 hereinafter more fully described.

The contact members 9 intermediate of the length thereof are secured to the walls 6 by means of screws 19 and the top sections 8 of said members are provided with binding screws 20 for securing an electrical connection, for instance a wire, thereto. The upper faces of the walls 6 are formed with recesses subjacent the screws 20 whereby to accommodate the shanks of the screws when the same are adjusted into binding position.

Mounted on the top of the switch box is a cover plate 21 and secured to said switch box by means of screws as at 22. Intermediate of the length thereof, the cover plate 21 is slotted and accommodates an actuating lever 23. Said lever is pivoted to said cover plate by means of a pin 24 journaled in eyes formed on the lower face of said cover plate adjacent the slot thereof.

The lower end of the lever 23 has secured thereto a shank having a ball head 25 secured within a collar 26 and said head and collar form a ball and socket joint. The collar is fashioned with a projection and forms a seat for retaining thereon the opposite end of the spring 18 heretofore described. Actuation of the lever 23 serves to move the collar 26 past the axes of the pivots 11 of the frame thereby compressing the spring 18 during the movement of the lever. As the spring moves past the axes of the pivots the frame will be oscillated in the opposite direction due to the tension exerted on the depending yoke 15 and thereby snap the blades 13 into or out of engagement with the contact members 9 as the case may be.

It is to be understood that any number of contact members may be secured to each side of the switch box and that the blades effect an electrical connection between all of the members upon movement to engaging position therewith.

From the foregoing it will be apparent that I have provided a snap switch constituted of a minimum number of parts and adapted for many purposes where a snap switch is desired, one instance being that of connecting the lights in each room of a building thereto whereby all of

said lights may be lighted at one time. This instance of use is advantageous in homes where it is desired to light all the rooms of the home at one time, for instance at night when it is thought that burglars may be entering the home.

It is to be noted that the action of the spring 18 not only effects a snap action for making and breaking an electrical connection between the contact members but also coacts with the lever 10 to maintain the frame through the medium of the pivots 11 in proper working position between the groups of contact members.

What I claim is:

1. A snap switch, comprising, a box having side 15 and end walls and an open top, spaced groups of contact members secured to said side walls respectively and extending into said box, an elongated frame having pivots pivoted to said end walls within said box and formed with connected 20 end and side bars, said side bars constituting contact blades and arranged between said groups of contact members for selective engagement therewith, a yoke connected to said end bars and depending therefrom, a cover plate secured over said box, a lever pivotally mounted on said plate and extending within said box above said yoke, a spring connecting said yoke to said lever and normally disposed to one side of the axes of the said pivots to cohibit pivoting of said frame, said spring operated by said lever to the opposite sides of said axes to effect pivoting of said frame and impart a snap action to said blades for making and breaking contact with said members.

2. A snap switch, comprising, a box having side 35 and end walls and an open top, spaced groups of contact members secured to said side walls respectively and extending into said box, said members on one side of said box formed with channels opening in one direction and those on the 40 opposite side formed with channels opening in the opposite direction, an elongated frame having pivots pivoted to said end walls within said box and formed with connected end and side

bars, said side bars constituting contact blades and arranged between said groups of contact members for selective engagement within the channels of said members, a yoke connected to said end bars and depending therefrom, a cover plate secured over said box, a lever pivotally mounted on said plate and extending within said box above said yoke, a spring connecting said yoke to said lever and normally disposed to one side of the axes of the said pivots to cohibit pivoting of said frame, said spring operated by said lever to the opposite sides of said axes to effect pivoting of said frame and impart a snap action to said blades for making and breaking contact with said members.

3. A snap switch, comprising, a box having side and end walls and an open top, spaced groups of contact members secured to said side walls respectively and extending into said box, said members on one side of said box formed with channels opening in one direction and those on the opposite side formed with channels opening in the opposite direction, an elongated frame having pivots pivoted to said end walls within said box and formed with connected end and side bars, said side bars constituting contact blades and arranged between said groups of contact members for selective engagement within the channels of said members, a yoke connected to said end bars and depending therefrom, a cover plate secured over said box, a lever pivotally mounted on said plate and having an end provided with a ball and socket joint extending within said box above said yoke, a spring connecting said yoke to said joint and normally disposed to one side of the axes of the said pivots to cohibit pivoting of said frame, said spring operated by said lever to the opposite sides of said axes to effect pivoting of said frame and impart a snap action to said blades for making and breaking contact with said members.

WILLARD RHEA.
